UNITED STATES PATENT OFFICE.

GEORG KIRKEGAARD, OF NEW YORK, N. Y.

BOTTLE-CAPPING MACHINE.

No. 844,028.

Specification of Letters Patent.

Patented Feb. 12, 1907.

Original application filed December 21, 1905, Serial No. 292,693. Divided and this application filed December 28, 1905.
Serial No. 293,277.

To all whom it may concern:

Be it known that I, GEORG KIRKEGAARD, a citizen of the United States, residing at the city of New York, in the borough of Brooklyn and State of New York, have invented 5 certain new and useful Improvements in Bottle-Capping Machines, of which the following is a full, clear, and exact description.

My invention relates to a machine for capping bottles.

The principal object of the present invention is to provide a machine for quickly associating and locking the caps upon the bottles without necessitating any difficult or 15 skilled manipulation.

With this and other objects in view my invention consists in the construction, combination, location, and arrangement of parts, as hereinafter set forth and shown, and finally pointed out in the appended claims.

Reference is also made to my generic application, Serial No. 292,693, filed December 21, 1905, of which this case is a division, and to my concurrently-pending divisional case, 25 No. 294,064, filed January 2, 1906.

In the drawings, Figure 1 is a side elevation of a complete machine embodying the principles of my invention. Fig. 2 is a similar view at right angles to the plane of Fig. 1. 30 Fig. 3 is a detail view showing part of the main operating-spindle. Fig. 4 is a detail view, partly in section, showing the cap in the process of being applied to a bottle. Fig. 5 is a detail view of a cam which forms a feature of my invention. Fig. 6 is a sectional view on the line VI VI, of Fig. 4, looking downward. Fig. 7 is a similar view on the line VII VII. Fig. 8 is a similar view on the line VIII VIII, and Fig. 9 is a similar view on 35 the line IX IX. Fig. 10 is a bottom view of a cap which may be applied by my bottle-capping machine.

My invention is particularly applicable to bottle-caps of the class set forth in my Patent No. 796,734, in which a cork-lined disk with depending fingers is adapted to be locked upon the bottle by the circumferential movement of a cam-ring which bears the fingers inward when turned. In the present 45 application I provide means for initially compressing the cap upon the bottle and subsequently turning the clamping-ring with the required amount of force regardless of irregularities in the cap or in the bottle.

Referring to the drawings, in which like parts are designated by the same reference-signs, 1 denotes an operating or power shaft journaled in the main frame 2 of the machine and having a gear 3 thereon meshing with the pinion 4. The pinion 4 is fixed to a short shaft 5, carrying a cam 6, which moves within a suitable groove 7 within the frame 2. 55 8 denotes a handle fixed to the shaft 1, whereby the gear 3 and the pinion 4, with its connected cam 6, may be oscillated when it is desired to operate the machine.

Upon the main frame 2 I erect a vertical standard 9, in which is guided a reciprocating rod 10, whereby the rod is normally spring-pressed upward and the roller 11 maintained 60 in contact with its cam. When, however, the handle 8 is rocked forward, the cam moves against the roller and depresses the rod within the standard.

Guided by brackets 15 on the standard 9 I 70 arrange what I shall term the "main operating-spindle" 16, having a cross-head connection 17 with the reciprocating rod 10. In this way the main operating-spindle is reciprocated within its brackets under the influence of the operating-handle 8. While I have shown this spindle reciprocating in this manner, I do not desire to be restricted thereto, since it may be reciprocated in any desired way.

The main operating-spindle 16 is made hollow throughout the whole or a portion of its length and contains a core 18, axially and circumferentially movable therein. I conveniently form the core 18 with a reduced portion 19 thereon screwed into and rigidly fixed to a terminal bearing portion 20.

21 indicates a collar included between the parts 18 and 20 of the core, so as to be circumferentially movable, and this collar has 95 lugs 22 guided in slots 23 within the main operating-spindle, so as to properly hold the core in place.

24 indicates a thrust-block, movable axially within the main operating-spindle under the influence of a spring 25, the tension of which may be adjusted to any amount by the adjusting-screw 26.

By the above arrangement the core 18 is capable of an inward movement with respect to the main operating-spindle against the tension of the spring 25 and is also capable of a free circumferential or rotary move-

ment by virtue of the swivel engagement with the collar 21.

To the lower end of the core 18 I attach the cap-applying head 27, the details of construction of which are particularly illustrated in Figs. 4, 7, and 8. As indicated in these figures, the preferred construction comprises a housing 28, formed to inclose a spring 29, secured thereto and to the core 18, so that the housing is held in a definite relation with respect to the core 18, but is capable of a rotary or circumferential movement from such position in case sufficient resistance is encountered. The housing is held in proper longitudinal relation upon the core 18 by collars 30 and 31, fixed thereto.

33 designates pawls which are hinged at points 34 about the housing 28 and depend through slotted guiding-lugs 35. The lower ends of each of these pawl-levers has an offset tooth or dog 36, which projects tangentially in a direction to apply locking-pressure to the clamping-ring of the bottle-cap. At additional points upon the housing 28 I secure depending spring-arms 37, with notched extremities 38, the purpose of which is to guide and hold the bottle-cap in proper relation with respect to the pawls 33.

39 designates springs secured to the slotted guiding-lugs 35, which exert a constant spring tension on the pawl-levers 33 to force them radially inward.

At the extreme lower end of the stud 18 I arrange an independently-revolute or swiveled bearing-plate 40, the lower surface of which is cupped, as shown at 41, so as to fit the upper surface of the bottle-cap.

42 indicates the swivel connection with the stud 18 and which has a circumferential groove 43, engaging a key 44 for holding the bearing-plate in position.

45 indicates balls within a ball-bearing raceway for permitting independent revulsive movement of the swiveled bearing-plate.

45 In addition to the features above described I provide means for imparting a certain predetermined movement to the stud 18 as the latter descends upon the bottle. For this purpose I have illustrated a practical construction in which a cam-blade 46 is rigidly secured to and depends from a portion of the main operating-spindle 16. The cam-blade 46 projects downward through a slot 47 in a transversely-movable rod 48, carrying a rack-section 49 and guided by the main frame of the machine.

50 indicates a tension-spring by which the reciprocating rod 48 is normally borne to the position shown in Fig. 6 of the drawings.

60 51 denotes a cam-roller held within the slot 47, and the relation is such that the cam 46 initially bears against the cam-roller 51 with its straight cam-surface 46' and is eventually moved to engage the same with its inclined surface 46'', which causes a trans-

verse movement of the reciprocating rod 48 against the tension of the spring 50.

52 designates a pinion splined to the stud 18 so as to rotate therewith and guided by the main frame of the machine, which meshes with the rack-section 49 above mentioned. In this way the motions of the rack are transmitted to the pinion and to the stud 18.

Directly beneath the main operating-spindle 16 and in line therewith I arrange a support or mat 53 for supporting bottles or receptacles to be capped. The position of this support or mat may be varied to any amount and subsequently clamped in such relation by the clamping-nut 54.

The operation is as follows: The operator being provided with a supply of bottles and suitable caps places a bottle upon the mat 53 and inserts a cap within the space between the various depending pawl-levers 33 until it abuts against the swiveled bearing-plate 40. In this relation it is grasped and held by the notches 38 of the depending spring-fingers 37. It is also engaged by the offset teeth or dogs 36 upon the pawl-levers directed into the notches of the milled clamping or locking ring of the cap, as shown in Fig. 9. If now the handle 8 is thrown forwardly, the cam 6 becomes effective to depress the main operating-spindle 16, with its contained core 18, until the swivel bearing-plate 40, with its cap, rests upon the top of the bottle. The main operating-spindle, however, continues to descend independently of the core, compressing the spring 25 and applying a pressure to the cap which forces it into proper sealing relation with the bottle. During this time the cam-roller 51 is engaged by the straight portion 46' of the cam 46, so that the pinion 52 does not have any turning movement. As the main operating-spindle continues to descend, however, the cam 46 is moved still further with respect to the cam-roller 51 until finally the inclined surface 46'' becomes effective to move the rack-section 49 transversely and rotate the pinion 52 through a portion of a revolution. By virtue of the splined connection of the pinion 52 with the core 18 the latter is also turned and the rotation is transmitted to the housing 28 by the intermediate spring 29. In this way the pawls 33 are carried around and serve to rotate the clamping-ring and firmly lock the cap upon the bottle. If on account of any irregularities or size or other reason any unusual resistance is encountered, the volatile spring 29 will yield sufficiently to relieve the abnormal force and prevent breakage of the bottle. When the operating-handle is reversely moved, the main operating-spindle is retracted upward; but in this movement the pawls 36 merely slip idly over the milled surface of the clamping-ring without disengaging it from the bottle, so that the cap is 130

left thereon in proper applied and sealing relation.

In Fig. 10 is shown in bottom plan view a bottle-cap capable of being secured upon a bottle by the above machine. The cap has a cork lining *a* and depending resilient fingers *b*, which are capable of engaging the usual bead upon a bottle-neck. *c* indicates a clamping-ring with a milled edge *d* and 10 which has internal cam-surfaces *e* to engage the various fingers *b*. It is evident that when this cam-ring *c* is turned through a part of a revolution that the cam-surfaces *e* will be effective to cam inward the various 15 depending fingers *b* and secure the cap upon the bottle.

What I claim is—

1. In a bottle-capping machine, a vertically-movable main operating-spindle, and a 20 pawl-carrying cap-applying head swiveled thereto and having a spring connection therewith to exert a turning force thereon.
2. In a bottle-capping machine, a vertically-movable main operating-spindle having a cap-applying head with depending 25 pawls, and means whereby said head is initially depressed and subsequently rotated.
3. In a bottle-capping machine, a vertically-movable main operating-spindle having a cap-applying head with depending 30 pawls, and means whereby said head is initially depressed and subsequently rotated by a non-positive connection with the main operating-spindle.
- 35 4. In a bottle-capping machine, a reciprocating main operating-spindle, a cap-applying head guided thereby and spring-pressed axially outward therefrom and carrying depending pawls, and means for imparting a final rotary movement to said cap-applying head.
5. In a bottle-capping machine, a reciprocating main operating-spindle having an independently-revolvable core spring-pressed 45 outward therefrom, and a cap-applying head having a spring connection with said core to exert a turning force thereon.
6. In a bottle-capping machine, a main operating-spindle having a core spring-pressed outward therefrom and carrying a cap-applying head, said head having a series 50 of depending pawls with teeth or dogs at their lower extremities for engaging a bottle-cap.
- 55 7. In a bottle-capping machine, a main operating-spindle having an independently-revolvable cap-applying head guided thereby, and rack-and-pinion connections for imparting a final rotary movement to the cap-applying head as the spindle is depressed.
8. In a bottle-capping machine, a main operating-spindle carrying an independently-revolvable cap-applying head, pawls depending from said head and guided thereby, a 60 cam, and rack-and-pinion connections for im- parting a final rotary movement to said cap-applying head.
9. In a bottle-capping machine, a main operating-spindle having a cap-applying head with depending pawl-levers, and depending spring-fingers intermediate said levers for grasping a bottle-cap. 7c
10. In a bottle-capping machine, a main operating-spindle having a cap-applying head, pawl-levers depending from said cap-applying head and having teeth offset or tangentially directed from their lower extremities. 75
11. In a bottle-capping machine, a main operating-spindle having a cap-applying head, pawl-levers depending from said head, and intermediate spring-fingers having notches for receiving and holding a bottle-cap. 8c
12. In a bottle-capping machine, a main operating-spindle having a cap-applying head at its lower end, spring means intermediate said head and spindle, and means for imparting a rotation to said cap-applying head through said spring means. 9c
13. In a bottle-capping machine, a main operating-spindle having a core projecting therefrom, a housing on said core, a spring connection between said core and housing, and pawls depending from said housing. 9.
14. In a bottle-capping machine, a cap-applying head having a central core and housing revolvable thereon, spring connections between said core and housing, and means for initially depressing the core and subsequently rotating it.
15. In a bottle-capping machine, a cap-applying head having a central core and an independently-revolvable housing, spring connections between said core and housing, and pawls depending from said housing and arranged to grasp the bottle-cap.
16. In a bottle-capping machine, a main operating-spindle having a depending cam-plate, a core projecting from said main operating-spindle and carrying a cap-applying head, and rack-and-pinion devices acted on by said cam-plate for imparting a rotation to said cap-applying head after the spindle has been depressed through a certain distance.
17. In a bottle-capping machine, a main operating-spindle having a core spring-pressed outward therefrom and carrying a cap-applying head, a cam-plate attached to said spindle, and rack-and-pinion connections for revolving said core after a certain predetermined movement of the main operating-spindle. 1
18. In a bottle-capping machine, a main operating-spindle having a depending cam-plate, a core spring-pressed outward from the main operating-spindle and carrying a cap-applying head, a rack and pinion guided by the frame of the machine, said rack being in the path of said cam-plate, whereby the 1

rack is moved when the main operating-spindle is depressed, said cap-applying head being connected to said pinion so as to rotate therewith.

- 5 19. In a bottle-capping machine, a main operating-spindle having a core spring-pressed axially therefrom and carrying a cap-applying head, and a collar swiveled upon said core and guided by said spindle.
- 10 20. In a bottle-capping machine, a main operating-spindle having a longitudinal groove therein, a collar having lugs guided in said groove, and a core having a cap-applying head, and swiveled in said collar and spring-pressed axially from the spindle.

21. In a bottle-capping machine, a main operating-spindle having a longitudinal groove, a collar having lugs guided by said groove, a core carrying a cap-applying head and having a reduced portion swiveled ²⁰ within said collar, and a cap upon said core for holding it in proper relation with the collar.

In witness whereof I subscribe my signature in the presence of two witnesses.

GEORG KIRKEGAARD.
